(57) **CLAIM**

We claim the ornamental design for an electronic device convertible case, as shown and described.

DESCRIPTION

FIG. 1 is a front perspective view of an electronic device convertible case;

FIG. 2 is a top plan view of the electronic device convertible case;

FIG. 3 is a bottom plan view thereof;

FIG. 4 is a left elevational view thereof;

FIG. 5 is a right bottom elevational view thereof;

FIG. 6 is a back elevational view thereof; and,

FIG. 7 is a front bottom elevational view thereof.

The broken lines represent stitching are part of the claim.
